UNITED STATES PATENT OFFICE.

ALPHONSO C. PRATT, OF MONTCLAIR, NEW JERSEY.

MACHINE FOR MAKING LINK MESH.

1,028,904.

Specification of Letters Patent.

Patented June 11, 1912.

Application filed September 12, 1911. Serial No. 648,876.

To all whom it may concern:

Be it known that I, ALPHONSO C. PRATT, a citizen of the United States, residing at Montclair, in the county of Essex and State 5 of New Jersey, have invented certain new and useful Improvements in Machines for Making Link Mesh, of which the following is a specification.

This invention relates to machines for 10 making link mesh and is especially adapted for use in machines of the type shown in United States Patent No. 948,615, granted to me February 8, 1910.

The invention is directed to the provision 15 of improved means for supporting the link mesh fabric during the operation of adding links thereto, and moving the fabric step by step so that the proper points thereon will be presented to the forming-tools at each 20 operation of the latter.

The invention involves the provision of 25 two members lying upon and coacting with opposite sides of the mesh, means for moving these two members and the mesh together in one direction and means for moving the mesh relatively to these members in another direction. During the operation 30 of making the link mesh, the finished mesh to which links are to be added may be supported in a plane or in a circle, but, in either case, the fabric must be moved after each 35 operation of the forming-tools so as to present to the tools the proper point on the fabric for receiving the next link; this movement of the fabric relatively to the tools must involve movement in two directions, the movement in the two directions being effected simultaneously or not as may be required by the type of machine adopted.

40 In the preferred embodiment of my invention the fabric to which the links are added is in the form of a sleeve and this sleeve is rotated step by step and moved axially a slight distance during each of such 45 steps. At the end of each step movement, the forming-tools operate to add one or more links to the mesh and therefore these links form one or more spirals extending around the sleeve of mesh. In my patent above referred to, the sleeve of fabric is supported 50 between a stationary mandrel having spiral grooves upon its exterior surface and a rotatable annular member surrounding the mandrel and having grooves upon its interior surface extending axially thereof. Dur-

ing the operation of the machine the annular member is rotated step by step, and the grooves on the interior surface thereof, coacting with grooves on the surface of the mesh, cause the mesh to be rotated with it. 60 During such rotation of the mesh the coaction of the inner surface thereof with the spirally grooved surface of the mandrel causes the requisite axial movement of the mesh.

In practice I have found it desirable to 65 more completely insure rotational movement of the mesh with the exterior rotatable member, and my present improvement involves a construction of the supporting 70 means for the fabric whereby the danger of faulty operation, due to failure of the fabric to move properly, is minimized.

The preferred embodiment of my invention is illustrated in the accompanying drawings in which—

Figure 1 is a central section of the machine, Fig. 2 is a detailed view of the ratchet feed for the mesh and Fig. 3 is an enlarged view, partly in section, of the supporting 80 devices for the mesh.

Referring to these drawings, 1 indicates a table on which is mounted a mandrel 2, a portion of which is provided with spiral grooves, the number of spiral grooves depending upon the number of pairs of forming-tools and the size of the grooves being proportioned to the size of the links used in making the mesh. A ring 3 is supported upon table 1 by means of posts 4 and forms a bearing for a sleeve 5 which fits within the ring. On the interior surface of the sleeve 5 are a plurality of ridges and depressions as shown at 6 in Fig. 2, these extending in the direction of the axis of the sleeve. On the exterior of sleeve 5 are formed ratchet teeth 7 adapted to be engaged by a pawl 8 pressed forward by the spring 9 in an opening formed in the shaft 10. This shaft extends downwardly through an opening in the post 4 and a bearing 11 secured to the frame of the machine and at its lower end is provided with a crank, the end of which coacts with a cam 15 secured upon the power-shaft 16. Thus, in each rotation 100 of shaft 16 and cam 15 the shaft 10 is rocked in its bearing and the pawl 8 carried thereby causes the sleeve 5 to rotate a distance equal to one of the teeth of ratchet 7 and in this position sleeve 5 is held by a spring- 110

pressed retaining pawl 17. The mandrel 2 is hollow and radial openings are provided therein, all in the same transverse plane. These openings receive reciprocating dies 18. Within mandrel 2 are spring-fingers 20, the ends of which engage dies 18 and tend to draw the dies inwardly. A plunger 21 is adapted to reciprocate within the opening in mandrel 2 and this plunger has cam surfaces 22 formed thereon such that when the plunger is raised these cam surfaces will engage the inner ends of dies 18 and force the dies radially outward. At its lower end plunger 21 is secured to a cross-head 23 having arms, the ends of which are pivotally connected to levers 24 whose outer ends are pivotally connected to levers 25 pivotally mounted upon the table 1. The cross-head 23 has a connecting rod 26 pivotally connected thereto and to cranks 27 upon the shaft 16. Each of the levers 25 operates a die-rod 30 and plunger 29 to coact with the oppositely disposed die 18 to form a link and mesh that link with links at the lower edge of the sleeve of fabric on mandrel 2 in the manner described in my patent above referred to.

It will be seen that the portion of the surface of mandrel 2 which is provided with the spiral grooves does not extend upwardly within the sleeve 5 a great distance. Instead, the mandrel 2 is reduced in size and a sleeve 31 is mounted for rotation thereon. Preferably this sleeve is provided with ball-bearings 32 so that it may rotate quite freely, the upper balls being held in place by a plate 33 secured to the top of the mandrel by a screw 34. The exterior surface of the sleeve 31 has grooves formed thereon and extending in the direction of the axis of the sleeve as shown at 35 in Figs. 2 and 3. The sleeve of fabric is supported between the two rotatable annular members or sleeves 31 and 5, its lower end extending down over the portion of the mandrel 2 which is provided with the spiral grooves. The axial ridges on the adjacent faces of the sleeves 5 and 31 enter corresponding axial depressions upon the surfaces of the fabric. For this reason, when member 5 is rotated step by step by the pawl and ratchet mechanism above described, the sleeve of fabric and the member 31 will rotate with it. By reason of the provision of rotatable members on both sides of the fabric, both provided with ridges entering the depressions in the fabric, the movement of the fabric with the sleeve 5 every time that sleeve is moved, and to the full extent to which the sleeve moves, is insured. As the fabric is so rotated step by step, the coaction of the spiral ridges on the mandrel 2 with spiral depressions in the surface of the fabric causes the fabric to be moved in the direction of its axis as it is rotated. In practice I have found that a

relatively small surface of the mandrel provided with the spiral grooves is sufficient to insure the axial movement of the fabric as the latter is rotated. With the mechanism here described the fabric will always be moved so as to present the proper point thereon to the forming tools for the reception of the next link or links to be added to the fabric.

Having described my invention, what I claim as new therein and desire to secure by Letters Patent of the United States is:

1. In a machine for making link mesh, a support for the mesh comprising two members on opposite sides of the mesh, means for moving said members and the mesh together step by step in one direction, and means for moving the mesh relatively to said members in another direction, substantially as set forth. 85

2. In a machine for making link mesh, a support for the mesh comprising two parallel members having their adjacent faces shaped to correspond with the surfaces presented by the mesh, said faces being adapted to engage the mesh, means for moving said members and the mesh together step by step in one direction, and means for moving the mesh relatively to said members in another direction, substantially as set forth. 95

3. In a machine for making link mesh, a support for the mesh comprising two members on opposite sides of the mesh, means for moving said members and the mesh together step by step in one direction, and means for causing the movement of the mesh with said members to move the mesh in another direction relatively to said members, substantially as set forth. 100

4. In a machine for making link mesh, the combination of two concentric rotatable members between which the mesh lies, means for rotating said members and the mesh between them, and means for moving the mesh axially relatively to said members, substantially as set forth. 105

5. In a machine for making link mesh, the combination of two concentric rotatable members between which the mesh lies, said members having their adjacent surfaces shaped to correspond with the surfaces presented by the mesh, means for rotating said members and the mesh step by step, and means for moving the mesh axially relatively to said members, substantially as set forth. 115

6. In a machine for making link mesh, the combination of two concentric rotatable members between which the mesh lies, said members having their adjacent surfaces shaped to correspond with the surfaces presented by the mesh, means for rotating said members and the mesh step by step, and a member which is stationary with respect to said members and which has a spirally 125

grooved surface coating with the mesh to move the latter relatively to said members, substantially as set forth.

7. In a machine for making link mesh, the combination of a member having a spirally grooved surface, a member rotatable adjacent to said surface and having grooves on its exterior surface extending substantially parallel to its axis of rotation, and a rotatable member inclosing said first-named

rotatable member and having grooves on its interior surface extending substantially parallel to its axis of rotation, substantially as set forth.

This specification signed and witnessed 15 this 9th day of September, 1911.

ALPHONSO C. PRATT.
